UNITED STATES PATENT OFFICE.

STEPHEN S. KRAYER, OF ST. LOUIS, MISSOURI.

GAS-ENGINE STARTER.

1,104,050.

Specification of Letters Patent.

Patented July 21, 1914.

Application filed August 30, 1912. Serial No. 717,981.

To all whom it may concern:

Be it known that I, STEPHEN S. KRAYER, a citizen of the United States, residing at the city of St. Louis, State of Missouri, have 5 invented a new and useful Gas-Engine Starter, of which the following is a specification.

This invention relates to gas engine starters and more particularly to a valve or 10 distributing device for starters, which is interposed between the fuel oil supply and the several cylinders of an engine.

An object of the invention is to provide a 15 simple and durable device of the character mentioned whereby a predetermined quantity of oil may be mixed with air and which carbureted air, by a simple manipulation of the valve, may be directly introduced into the cylinders of an engine, in proper 20 sequence, under sufficient pressure to put the gas under compression in the cylinders. After which it may be ignited by usual means, effectively to start the operation of 25 the engine.

With this and other obvious ends in view 30 I have designed, combined and arranged the several coöperating parts, comprising my present invention, in the manner hereinafter described and illustrated in the drawings, in which—

Figure 1 is a section through the valve case and the valve plug carrying the oil chambers, showing the several coöperating pipe connections. Fig. 2 is a vertical section through the device, showing one of the oil chambers in a position to inject a charge of carbureted air into a cylinder. Fig. 3 is a semi-diagrammatic view comprising a vertical section of the case with the valve 35 plug removed, the valve plug, and an end elevation of the valve case viewing certain of the gas outlet passages in elevation, a part of said case being broken away to show the gas outlet openings through the valve case, the passage of the air and gas being indicated by the distinctive lines. Fig. 4 is a 40 fragmentary vertical section of the valve case with the valve plug removed, showing the oil inlet passage and the distributing groove in the case. Fig. 5 is a vertical section through the valve case and valve plug, a portion of the valve plug being broken away so as to more clearly illustrate the oil 45 inlet passages for the oil leading to the several oil chambers. Fig. 6 is a view of

the same parts as are disclosed in Fig. 5 viewed from the opposite side of the case, disclosing the oil outlet passages. Fig. 7 is a horizontal section of a fragment of the device illustrating the oil inlet passages, 60 and a detail of one end of the oil chambers carried by the valve plug. Fig. 8 is a fragmentary horizontal section of the valve plug, showing the outlet end of one of the oil chambers carried therein, and Fig. 9 is 65 a fragmentary view illustrating the outlet end of one of the oil chambers carried by the valve plug.

In the embodiment of my invention illustrated in the drawings, 1 indicates the casting which is provided with a tapering valve seat 2 and with a removable cover 3. The cover 3 is provided with an interiorly threaded hollow boss 4 through which the stem of the valve plug 5 projects. In order to effect a tight closure, packing material 6 is placed around the stem of the valve plug and an exteriorly threaded nut 7 is screwed into the threaded boss 4. A removable handle 8 surmounts the stem of the valve 80 plug 5 whereby the same may be manipulated. The valve case has a passage 9 through the wall thereof, said passage constituting an oil inlet. The passage 9 is tapped at its outer end to receive a threaded 85 oil supply pipe 10. Diametrically opposite to the said inlet passage 9 is an outlet passage 11 which is likewise threaded at its outer opening to receive the threaded oil outlet pipe 12. At the side of the valve case 90 intermediate the oil inlet and outlet passages is a third passage 13 tapped to receive a threaded air inlet pipe 14. The said air inlet passage has an L-shaped branch passage 15 leading therefrom to the interior 95 of the valve case. Through the wall of the valve case, opposite to the air inlet passages, are formed a plurality of gas outlet 100 passages 16. The arrangement of the outlet passages is such that certain thereof are in the same plane as the upper branch of the air inlet and certain of them in the same plane as the lower branch of the air inlet; said passages being arranged in staggered 105 relationship, as clearly illustrated in Fig. 1 of the drawings. Radiating from the inner opening of the oil inlet passage 9 are channels or grooves 17 formed in the interior surface of the valve case. At the opposite side, communicating with the interior open- 110

ing of the oil outlet passage is a second series of grooves or channels 18. The arrangement of the oil inlet passage and the oil outlet passage with their respective communicating grooves or channels 17 and 18, is such that oil entering the inlet passage will be distributed by means of the grooves or channels 17 to the oil chambers carried by the valve plug, through which it flows and is discharged into the grooves or channels 18, from thence it flows to the outlet passage 11, when the valve plug is in normal adjustment, as shown in full lines in Fig. 1 of the drawings.

15 The oil chambers 19, that are carried by the valve plug, comprise a series of openings or bores extending through the valve plug and are so arranged that when the valve plug is seated in its valve seat that certain ones of said chambers will be in the same plane as the upper branch of the air inlet and certain ones will be in the same plane with the lower branch of the air inlet. The oil inlet ends of the chambers are restricted 25 as shown at 20 in Fig. 7 and the opposite ends of said chambers are threaded as shown at 21. The inlet openings of the oil chambers are arranged in a rectangular series and the chambers pass obliquely through the valve plug so that the outlet ends thereof constitute a staggered series of openings arranged as shown in Fig. 6 of the drawings. Each of the chambers 19 is 30 provided with a removable threaded plug 22 which has a passage 23 therethrough. In assembling the parts of the device a quantity of wire gauze 24 is bent and packed into the several chambers 19 and the plugs or caps 22 are then inserted to close the chambers and 35 to keep the gauze in place, the oil passing through the passages 23. Each of the plugs or caps 22 is provided with a transverse groove 25 to receive a screw-driver or suitable instrument for adjusting the same with- 40 in the threaded ends of the chambers. It is apparent that the capacity of each oil chamber may be varied by manipulation of the plug or cap 22. The purpose of the gauze 24, within the chambers 19, is to permit the 45 oil to be more readily mixed and vaporized when the air from supply pipe passes therethrough.

I prefer to place the device in a vertical 50 position such as is shown in Fig. 1. The oil enters through the supply pipe 10 and the 55 passage 9 and flows by gravity, by way of the grooves 17, into the several chambers 19 thence through the grooves or channels 18 to the outlet passage 11 and thence to the 60 outlet pipe 12. It will be understood that the inlet passage 9 should be placed on a lower level than the oil tank from which oil is supplied to the pipe 10, so that the oil when the valve is in normal adjustment will 65 continuously flow through the several pas-

sages into the outlet pipe 12, which may be connected with the usual carburetor. Thus it will be seen that the oil chambers are always charged with oil. When it is desired to inject gas into the cylinders of the 70 engine the valve plug 5 is manipulated by the handle 8 so that the oil chambers will be brought into registration at one end with the air supply passage, and at the other end with the respective gas outlet passage. The 75 air which is supplied through the pipe 14 is under sufficient pressure to vaporize the oil in the oil chambers and to force the carbureted air or gas into the gas outlet passages, thence it is conducted to the respective cylinder of the engine with which the specific outlet pipe 26 communicates. The 80 passage of the air from the supply pipe 14, through the oil chambers to the gas outlet passages will be clearly understood by reference to Fig. 3, which view illustrates in detail the manner in which the several ports register as the valve plug is operated. It 85 will be noted by reference to Fig. 1 that all the passages may be closed by bringing the 90 valve plug to a neutral position by turning the handle 8 one eighth of a turn from the position shown in dotted lines in this figure of the drawings. It will, of course, be understood that as soon as the handle is moved 95 from the normal position shown in Fig. 1, the oil inlet and outlet passages will be closed.

Having thus fully described my invention, what I claim and desire to secure by Letters Patent is:

1. A device of the character described, comprising a valve case, oil inlet and outlet passages entering said case, an air inlet passage, a plurality of gas outlet passages, a valve plug, oil chambers formed in said valve plug, and means for manipulating said valve plug to bring said chambers into communication with said oil inlet and outlet passages, and then to bring said chambers into registration with said air inlet and gas outlet passages, in succession, substantially as specified.

2. A device of the character described, comprising a valve case, an oil inlet passage, an oil outlet passage arranged opposite to said oil inlet passage, an air inlet passage comprising two branches arranged in vertical alinement, a plurality of gas outlet passages arranged in parallel series, certain of said passages being in the same plane as the upper branch of said air inlet and certain thereof in the same plane as the lower branch of said air inlet, a valve plug, and a plurality of oil chambers in said valve plug arranged in two parallel planes 120 and entering said plug in a rectangular series and opening out of said plug in a staggered series, and means for manipulating said valve plug to communicate said oil inlet and outlet passages, and to communi- 125 130

cate said air inlet passage and selected ones of said gas outlet passages, substantially as specified.

3. A device of the character described, comprising a valve case, an oil inlet passage, an oil outlet passage arranged opposite to said oil inlet passage, an air inlet passage comprising two branches arranged in vertical alinement, a plurality of gas outlet 10 passages arranged in parallel series, certain of said passages being in the same plane as the upper branch of said air inlet and certain thereof in the same plane as the lower branch of said air inlet, a valve plug, a plurality of oil chambers in said valve plug arranged in two parallel planes and entering said plug in a rectangular series and opening out of said plug in a staggered series, and means for manipulating said 15 valve plug to communicate said oil inlet and outlet passages, and to communicate said air inlet passage and selected ones of said gas outlet passages, and a packing of wire gauze in each oil chamber, substantially as specified.

4. A device of the character described, comprising a valve case, an oil inlet passage, an oil outlet passage arranged opposite to said oil inlet passage, an air inlet passage 30 comprising two branches arranged in vertical alinement, a plurality of gas outlet passages arranged in parallel series, certain of said passages being in the same plane as the upper branch of said air inlet and certain thereof in the same plane as the lower branch of said air inlet, a valve plug, a plurality of oil chambers in said valve plug arranged in two parallel planes and entering said plug in a rectangular series and opening out of said plug in a staggered series, and means for manipulating said 35 valve plug to communicate said oil inlet and outlet passages, and to communicate said air inlet passage and selected ones of said gas outlet passages, a packing of wire gauze in each oil chamber, and an adjustable cap for each chamber, substantially as specified.

5. A device of the character described, comprising a case, oil inlet and outlet passages, a valve plug, an air supply, gas outlet 50 passages, an oil chamber carried by said valve plug, and means for manipulating said valve effectively to selectively communicate said oil chamber with said oil in-

let and outlet passages, and with said air inlet and gas outlet passages, substantially as specified.

6. In a starting device, the combination with a hydrocarbon liquid supply passage 60 and a hydrocarbon outlet passage, of an air supply passage, a chamber carrier revolvable with respect to said passages, chambers in said carrier, means for moving said carrier and a plurality of gas outlet passages 65 arranged to be communicated with said chambers when the opposite end of each is brought into registration with said air supply passage, substantially as specified.

7. A starting device comprising a case, 70 a liquid supply passage entering said case, a liquid outlet passage leading from said case, an air inlet passage, gas outlet passages, liquid chambers and means for moving said liquid chambers whereby the exit 75 ends of said liquid chambers will register with the outlet passage when the inlet ends of said chambers register with the liquid inlet passage, and for moving such chambers to such adjustment that the exit end of 80 said chambers will communicate with said gas outlet passages, in succession, while their respective inlet ends register with said air inlet passage, substantially as specified.

8. The combination with a valve case provided with an oil inlet and outlet passage and an air inlet and gas outlet passage, of a valve plug mounted therein, said valve plug carrying a series of oil chambers, and means for manipulating said valve for the purpose 90 set forth, substantially as specified.

9. A device of the character described comprising, in combination, a case, an oil inlet passage to said case, an oil outlet passage from said case, a valve plug mounted 95 in said case, an air supply, a gas outlet passage from said case, an oil chamber arranged in said valve plug, and means for operating said valve plug effectively to communicate said oil chamber with said oil 100 inlet and said oil outlet passage and with said air inlet and gas outlet passage, substantially as specified.

In witness whereof, I have signed this specification in the presence of two sub- 105 scribing witnesses.

STEPHEN S. KRAYER.
